UNITED STATES PATENT OFFICE.

ANDREW J. GILBERT, OF NEW YORK, N. Y., ASSIGNOR TO THE UNION STOVE
AND MANUFACTURING COMPANY, OF PITTSSTON, PENNSYLVANIA.

DESIGN FOR A COOKING-STOVE.

Specification forming part of Design No. 6,238, dated November 5, 1872.

To all whom it may concern:

Be it known that I, ANDREW J. GILBERT, of the city, county, and State of New York, have invented a new and original Design for a Stove called "Our Choice," of which the following is a specification:

This invention relates to a new form of ornaments on the side doors of a cooking-stove, said ornaments being arranged in the door-

corners, around oval center-pieces embracing shields, all as shown.

I claim as my invention—

The design for the side doors of a stove, as shown.

ANDREW J. GILBERT.
